(57) **CLAIM**

The ornamental design for an external hard drive housing, as shown and described.

DESCRIPTION

FIG. 1 is a perspective view of an external hard drive housing showing our new design;

FIG. 2 is a front elevational view thereof;

FIG. 3 is a rear elevational view thereof;

FIG. 4 is a left side elevational view thereof; and,

FIG. 5 is top plan view thereof.

The broken lines showing of the remainder of the external hard drive housing are for the purpose of illustrating unclaimed portions and form no part of the claimed design.
